UNITED STATES PATENT OFFICE.

VICTOR GABRIELE, OF ALBUQUERQUE, NEW MEXICO.

BLADE-SHARPENING DEVICE.

Application filed December 9, 1922. Serial No. 605,904.

To all whom it may concern:

Be it known that I, VICTOR GABRIELE, a subject of the King of Italy, residing at Albuquerque, in the county of Bernalillo 5 and State of New Mexico, have invented new and useful Improvements in Blade-Sharp-ening Devices, of which the following is a specification.

The object of my said invention is the 10 provision of a simple, inexpensive and easily operated device through the medium of which safety razor blades may be expeditiously and efficiently honed or stropped so that increased service can be obtained 15 from each blade, thereby obviating the waste due to the discarding of a safety razor blade after the same has been used a couple of times.

To the attainment of the foregoing, the 20 invention consists in the improvement as hereinafter described and definitely claimed.

In the accompanying drawings, forming part of this specification:—

Figure 1 is an elevation showing one side 25 of my novel device.

Figure 2 is an elevation showing the opposite side of the device.

Figure 3 is a top plan of the device.

Figure 4 is an end view of the device.

Figure 5 is a detail transverse section 30 hereinafter explicitly referred to.

Similar numerals of reference designate corresponding parts in all of the views of the drawings.

Among other elements my novel device 35 comprises a plate 1, preferably of appropriate metal. To the said plate 1 is fixedly connected a handle 2, the connection being preferably effected by threading a reduced end of the handle 2 into the plate 1 as illus- 40 trated.

An appropriate honing stone 3 is ar- 45 ranged above and disposed at an acute angle to the plate 1, and it will be noted that the plate 1 is provided at one of its side edges and at its ends with standards 4; also, that connected by screws 5 or other appropriate means to the standards 4 is a slotted rail 6, i. e., a rail having longitudinal portions in 50 parallelism and also having a space between the said longitudinal portions. A bolt 7 is extended loosely through an aperture in the plate 1 and is appropriately fixed to the stone 3 so as not to protrude above the sur- 55 face of the said stone. Said bolt 7 is threaded for the engagement of a nut 8 disposed

below the plate 1, and mounted on the bolt 7 and interposed between the plate 1 and the stone 3 is a coiled spring 9 which operates to yieldingly support the comparatively high end portion of the stone 3 so as to contribute to the blade sharpening capacity of the stone. The comparatively low portion of the stone is appropriately connected at the point 10 to the plate 1, and at said point a rubber washer 11 is interposed between the plate and the stone, the said washer 11 being preferably retained in position by the bolt or rivet used at the point mentioned in connecting the stone to 60 the plate 1. Manifestly by adjusting the nut 8, the user is enabled to depress or raise one end of the stone to regulate the stone for use in conjunction with safety razor blades of different kinds.

Associated with the rail 6 is a carriage 12, on which is a handle 13 to enable the operator to conveniently move the said carriage lengthwise of the rail. The said carriage 12 is equipped with a roller 14 in engagement 80 with the rail to render easy the movement of the carriage in opposite directions on the rail. At 15 is a safety blade holder, which is detachably connected preferably by a set screw 16 in the manner illustrated so 85 that it can be removed to give place to other holders, with the result that the honing device is adapted to hone safety razor blades of all kinds.

As best shown in Figure 5 the roller 14 is 90 fixed on a shaft 17 one end of which is adapted to be socketed in the tubular shank of the blade holder 15 and to be engaged by the set screw 16. On the outer end of the shaft 17 is fixed a spur gear 18.

In the practical use of my novel device the safety razor blade is disposed in the holder 15, and the holder is moved through the medium of the means described relative to the stone 3 when the blade will be expeditiously and thoroughly honed, the blade being turned at the end of each traverse. The inclination of the stone or hone 3 to the plate 1 and the rail 6 assures gradual increase of pressure of the stone against the blade when the blade is moved lengthwise of the stone in one direction, and gradual lessening of said pressure when the blade is moved in the opposite direction.

When the device is to be used for strop- 110 ping purposes, a strop (not shown) is ar- ranged lengthwise above the stone 3, and the

blade holder is transferred from the shaft 17 to an upper shaft 19 in the carriage 12, said shaft 19 having a gear 20 meshed with the gear 18 that the blade in the holder will 5 be properly disposed for stropping purposes and will be reversed incident to its traverses on the strop. Manifestly when desired the shaft 19 can be removable.

Notwithstanding the practical advantages 10 of my novel device it will be noted that the same is simple and inexpensive in construction and embodies no delicate parts such as are likely to get out of order after a short period of use.

15 I have entered into a detailed description of the construction and relative arrangement of the parts embraced in the present and preferred embodiment of my invention in order to impart a full, clear and exact 20 understanding of the said embodiment. I do not desire, however, to be understood as confining myself to the specific construction and relative arrangement of parts inasmuch as in the future practice of the invention

various changes and modifications may be 25 made such as fall within the scope of my invention as defined in my appended claim.

Having described my invention, what I 30 claim and desire to secure by Letters-Patent, is:—

A device for honing safety razor blades comprising a plate bearing a handle, a honing stone connected with and yieldingly supported on the plate at an angle thereto, a rail carried by the plate, a handle movable relative to and associated with the rail, and a blade holder connected with the handle; the said connection including a roller in engagement with the rail, and a shaft carrying the roller and equipped at its outer end with a spur gear and adapted at its inner end for the detachable fixture of the blade holder, and a second shaft in the handle and having a spur gear at its outer end and its inner end adapted to be connected to the 45 holder.

In testimony whereof I affix my signature.
VICTOR GABRIELE.
